ADJUSTABLE SPANNER WRENCH

Clarence L. Meyer, Dayton, Ohio

Application January 11, 1944, Serial No. 517,804

3 Claims. (Cl. 81—90)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a spanner wrench and particularly to a wrench of this class which is adjustable to different sizes. An object of the invention is to provide a single wrench with such adjustments as will enable it to cover a range of work which ordinarily would require a considerable number of separate wrenches.

Another object is to so construct and arrange the wrench that it will require a minimum of time to adapt it to the several uses to which it is applicable.

Another object is to so construct the wrench that it may be gotten into narrow spaces between hubs or similar parts which may be spaced along a shaft.

Another object is to provide a wrench which will have capacity to adjust nuts in difficult positions which an ordinary wrench will not reach.

I attain these and other objects in the devices hereinafter described and shown in the drawings wherein:

Fig. 1 is a top plan view of the improved wrench with the cover plate broken away on the left half to show the interior construction;

Fig. 2 is an edge view, the lefthand portion being a section taken at 2—2 of Fig. 1;

Figs. 3, 4, 5 and 6 show examples of interchangeable adapters used for adapting the wrench for adjusting different kinds of nuts;

Figs. 7, 8 and 9 are examples of nuts having different indentations for receiving the lugs of the wrench;

Fig. 10 shows a nut of special design which requires a special adapter;

Fig. 11 shows a nut in a particular location which makes it difficult to adjust with a wrench of ordinary construction;

Fig. 12 shows one of a pair of adapters which may be used for adjusting hexagonal or other polygonal nuts.

Referring to the drawings, the body of the wrench is made in two substantially identical parts 10, hinged together by hinge pin 12 and fastened at a point opposite the hinge pin by a locking bolt 14. Two slide members 16 are longitudinally movable in the body 10, the body parts 10 being milled out to provide a channel as at 17 as a guiding means for the slide members.

In order to more easily mill out the guiding surfaces for the slide members 16, the body portions 10 are provided with removable covers 18

on the front surfaces, the covers being fastened to the body parts by means of screws 20. The cover on the left half of the body is shown broken away (see Fig. 1). Openings 22 are cut through both the body part 10 and the cover 18 for the adjusting nuts 24, the slides 16 being provided at their outer ends with long screws 26, the external threads of which fit the internal threads of the adjusting nuts. Each body portion 10 is provided with a handle 28 which, in the exemplification shown, is welded to the part 10, although where it is desired to carry the outfit in a smaller package, arrangement may be made for screwing the handles into place. Obviously, turning the nuts 24 will move the slides longitudinally in the channels of the wrench body to alter the distance between the inner ends of the slides.

The inner ends of the slides 16 are each provided with a transversely extending socket 30 arranged and positioned to receive a series of interchangeable adapters, one example 32 being shown in place in Figs. 1 and 2, other examples being disclosed in Figs. 3, 4, 5 and 6. Each adapter 32 has extending from its under side a rectangular shank 34 (see Fig. 2) which is fitted slidably to the socket 30, while its upper surface carries a lug 36 of a size and contour suitable for entering the wrench-lug opening in the nut which is to be adjusted.

30 The nut 38 (see Fig. 7) is of a type to which the adapter 32 is suitable, the nut 38 having a series of round wrench-lug openings 40 into which the round lugs 36 of the adapter may enter when the nut is to be adjusted, the slides 16 being, of course, 35 adjusted longitudinally until the spacing of the lugs 36 equals the pitch diameter of the openings 40. The additional adapters shown in Figs. 3 to 6 are for other types of nuts. For instance, the adapter 42 (see Fig. 4) is provided with square lugs 44 which may be used in tightening nuts having wrench-lug openings in the form of radial grooves 46 in their front faces as in the nut 48 of Fig. 8. Where a nut has a series of axially extending grooves 50 around its periphery, such as 45 appear in the nut 52 of Fig. 9, adapters as shown at 54 are provided with longitudinal key parts 56, which are designed to fit the grooves 50 in the nut 52.

In cases where a nut, such as the nut 55 of Fig. 50, is of relatively small diameter and has wrench-lug openings in the form of radial grooves in its front face, it may be necessary to provide a pair of offset adapters 58, as seen in Fig. 3, in order to allow the inner ends of the slide members 16 to clear the shaft 60 upon which the nut

55 is being adjusted. One of a pair of offset adapters 58 is shown in Fig. 3.

There are occasions where a nut like that shown at 62 of Fig. 11 is located at the bottom of a cupped member 64. In such case it becomes necessary to provide extension adapters 66 as shown in place in Fig. 11 and in detail in Fig. 6. Such adapters will carry lugs 68 on their forward ends adapted to fit the lug-engaging slots of the nut. They should also have threaded stud portions 70 at their rearward ends which may be provided with nuts 72. These nuts are provided only on extension adapters, and are required because of the considerable leverage tending to pry the adapters out of their sockets in the slides.

The slides are each provided with a small spring-and-ball detent 74, Fig. 1, each adapter having a corresponding depression 75 for the ball to enter, whereby, for the ordinary adapters, no other fastening means is required. Special adapters, as shown at 76, Fig. 12, may be provided for hexagonal or other polygonal nuts, these adapters being provided with sides to fit the angle of the polygonal nuts which are to be adjusted, the rectangular shanks 34 being of the same dimensions as the other adapters heretofore described.

The fact that the wrench may be opened, as shown by the dotted line 77 of Fig. 1, makes it particularly applicable to the adjustment of aircraft parts, such as landing gears, tail wheels, struts, etc., without taking them from the airplane, because the structure of many of these parts is such that a solid wrench may not be gotten to the nut which is to be adjusted from either end.

A graduation 78 may be put on the top of the slide members 16 adjacent the opening in the body 12, whereby the size to which the wrench

is to be adjusted for a given part may be predetermined. The part numbers of the nuts which are to be adjusted may be used as indicia opposite the several graduations, to facilitate adjustment of the wrench for a particular part.

I claim:

1. For adjusting nuts of different sizes and types, an adjustable spanner wrench which comprises a body having oppositely extending handle portions and a central opening to receive the parts which carry the nuts to be adjusted, a pair of opposite slide members carried by said body, normal to the axis of said central opening, slideable in a groove of said body, said members having their inner ends projected into said central opening, screw-and-nut adjusting means associated with the outer ends of each of said members for varying the distance which each slide member projects into said opening, the slide members having rectangular sockets extending transversely therethrough adjacent the inner ends, detent means extendable inwardly into said sockets, adapters having shanks at one end extending into said sockets with detent depressions for cooperating with said detent means, and lugs at the other end for engaging wrench-lug openings in the nuts which are to be tightened.

2. The wrench of claim 1 in which the body is divided into two parts on a line extending diametrically through the central opening with hinge means joining the two parts on one side and removable locking bolt means joining the two parts on the opposite side.

3. The wrench of claim 1, with graduations on the slide members alignable with the edge of said central opening, and with the part numbers of the nuts to be adjusted carried as indicia for the several graduations.

CLARENCE L. MEYER.
